UNITED STATES PATENT OFFICE.

THEODORE L. VALERIUS AND OLAF LARSEN, OF FORT ATKINSON, WISCONSIN,
ASSIGNORS TO THE CREAMERY PACKAGE MFG. COMPANY, OF CHICAGO,
ILLINOIS, A CORPORATION OF ILLINOIS.

LOCK FOR CHURN COVERS.

Application filed March 6, 1918. Serial No. 220,734.

To all whom it may concern:

Be it known that we, THEODORE L. VALERIUS and OLAF LARSEN, residing at Fort Atkinson, in the county of Jefferson and State 5 of Wisconsin, have invented certain new and useful Improvements in Locks for Churn Covers, of which the following is a specification.

Rotary churns are provided with cylindrical bodies formed of wood, the body having 10 an opening in its cylindrical wall through which cream, wash water and salt are placed in the churn and the butter removed.

The present invention relates to an improved cover for such an opening and to improved means for locking the cover in closed position.

In the accompanying drawings, Figure 1 is a plan view of a construction embodying 20 the features of our invention. Fig. 2 is a sectional view taken in the plane of dotted line 2—2 of Fig. 1. Fig. 3 is a section on line 3—3 of Fig. 1. Fig. 4 is a fragmental sectional view on dotted line 2—2 of Fig. 1, 25 on an enlarged scale.

In Fig. 2, A denotes a portion of the cylindrical wall of a churn. In said wall is formed an opening B. A frame 1 is rigidly secured to the wall A, said frame comprising 30 a flange 2 that overlies the margin of the opening B and is rigidly secured to the wall A in any suitable manner. The inner portion 3 of the frame 1 is depressed, and in said inner portion is formed an oblong opening 4 that affords access to the interior of 35 the churn.

The cover 5 for closing the opening 4 is hinged to the frame 1 in a suitable manner. Herein the cover is shown as secured to two 40 hinge members 6 which are pivotally secured to the frame 1 at 7, the hinges being located at one of the longer sides of the cover. The cover 5 is provided with a marginal packing strip 8 of any suitable 45 material, which, when pressed against the inner portion 3 of the frame 1, forms a tight joint between the cover and the frame.

The means for locking the cover 5 in closed position comprises a plurality of arms 50 pivotally connected to the cover and adapted to be forced beneath lugs on the frame 1, so as to hold the packing 8 tightly against its seat. In the present embodiment of the invention, there are two sets of arms, the

arms of each set being rigidly connected 55 together and the two sets being arranged to be simultaneously moved. Each set consists of three arms 9, 10 and 11, the arm 9 being arranged to bear against the side of the cover opposite to the hinges, the arm 11 60 being arranged to bear against the cover adjacent to the hinges, and the arm 10 being arranged to bear against the end of the cover. The arms 9, 10 and 11 are rigidly connected together and are pivotally secured 65 to the cover by means of a screw-stud 12. The end of the arm 9 is beveled and is arranged to be forced beneath a locking lug 13 on the frame 1. The ends of the arms 10 and 11 are similarly beveled and are arranged 70 to engage beneath locking lugs 14 and 15, respectively, on the frame.

Rigid with each set of arms 9, 10 and 11 is an arm 16 extending at right angles with the arms 9 and 11, and provided with a segment 17 that meshes at all times with a pinion 18. The pinion 18 is provided with a pivot or journal 19 which is rotatably mounted in a central bearing 20 on the cover 5. The pinion is held against end- 80 wise displacement by means of two curved plates 21 secured to the arms 16 and overlying the teeth of the segments 17 and the pinion 18.

Any suitable means may be provided for 85 turning the pinion 18 to swing the two sets of arms 9, 10 and 11. Herein is shown what is, in effect, a double-handled wrench, the handles being represented at 22 and the middle portion of the wrench having a 90 serrated opening 23 to fit upon a similarly serrated member or pinion 24 formed integral with the pinion 18. The member 24 is made in the form of a pinion merely for convenience of manufacture. 25 is a disk 95 secured to the upper end of the member 24 and overlying the central portion of the wrench to secure the wrench to said member. It will be seen that by rotating the wrench, the two sets of arms 9, 10 and 11 will be 100 pivotally moved into and out of engagement with the locking lugs 13, 14 and 15. When it is desired to gain access to the interior of the churn for any purpose, the wrench is turned in the direction to move the arms 9, 105 10 and 11 out of engagement with the locking lugs, whereupon the cover may be swung upon its hinges away from the opening 4.

When said opening is to be closed, the cover 5 is swung into the position shown in the drawings and the wrench turned to force the sets of arms 9, 10 and 11 beneath the 5 locking lugs 13, 14 and 15, thereby forcing the packing 8 tightly against the margin of the opening 4.

Each set of arms 9, 10, 11 and 16 constitutes a cruciform lever.

- 10 It will be seen that since the cover is hinged to the churn, the annoyances incidental to a loose or detached cover, are avoided. The locking devices, being permanently secured to the cover, are always at 15 hand, ready for operation to lock or unlock the cover. The rigid metallic frame 1 provides a rigid and substantial seat for the cover.

We would have it understood that the 20 foregoing detailed description is not intended to limit our protection, the scope of the patent being indicated in the appended claims.

We claim as our invention:

- 25 1. In combination, a churn body, a frame attached to the body and having an oblong opening, an oblong cover for closing the opening, one of the long sides of the cover being hinged to the frame, two cruciform levers pivotally secured to the cover, each lever comprising three locking arms, lugs on the frame for engagement by said locking arms, each lever further comprising an arm extending toward the corresponding arm of the other lever, a gear segment on each of the last mentioned 35 arms, a pinion pivotally mounted upon the cover and meshing with both of the said segments, and means for turning the pinion.

40 2. In combination, a churn body, a frame attached to the body and having an oblong opening, an oblong cover for closing the opening, two cruciform levers pivotally secured to the cover, each lever comprising three locking arms, lugs on the frame for engagement by said locking arms, each lever further comprising an arm extending toward the corresponding arm of the other lever, a gear segment on each of the last mentioned arms, a pinion pivotally mounted upon the cover and meshing with both of the said segments, means to hold the pinion against 45 endwise displacement, and a wrench fixed to said pinion.

- 45 3. In combination, a churn body, a frame attached to the body and having an oblong opening, an oblong cover for closing the opening, two cruciform levers pivotally secured to the cover, each lever comprising three locking arms, lugs on the frame for engagement by said locking arms, each lever further comprising an arm extending toward the corresponding arm of the other lever, a gear segment on each of the last mentioned arms, a pinion pivotally mounted upon the cover and meshing with both of the said segments, means to hold the pinion against 50 endwise displacement, and a wrench fixed to said pinion.

endwise displacement, and a wrench fixed to said pinion.

55 3. In combination, a churn body, a frame attached to the body and having an opening, a cover adapted to lie against the outer side 60 of the frame to close the opening, said cover being hinged to the outer side of the frame, a lever pivotally secured to the cover and comprising a plurality of locking arms, lugs on the frame for engagement by said locking 65 arms, and means connected to the cover and operatively engaging the free end of the operating arms for swinging said arms into and out of engagement with the lugs.

4. In combination, a churn body, a frame 70 attached to the body and having an oblong opening, an oblong cover for closing the opening, two levers pivotally secured to the cover, each lever comprising a plurality of locking arms, lugs on the frame for engagement 75 by said locking arms, each lever further comprising an arm extending toward the corresponding arm of the other lever, a gear segment on each of the last mentioned arms, a pinion pivotally mounted upon the 80 cover and meshing with both of the said segments, and means for turning the pinion.

5. In combination, a churn body with an opening in one wall, a cover for closing said opening, a member movably positioned 85 on said cover and comprising a plurality of arms rigid with reference to each other, certain of said arms being adapted to operatively engage with said wall to secure said cover in closed position, and gear means 90 mounted on the cover in operative engagement with one of said rigid arms whereby said securing arms may be positively swung into and out of securing engagement with said wall.

95 6. In combination with a churn having an opening, a frame secured about said opening, a cover operatively supported upon said frame and adapted to seal the opening, a pair of locking levers pivoted on said 100 cover and arranged to operatively engage said frame to secure said cover in sealed position, gearing supported on said cover and having operative engagement with both of said levers, and means for actuating the 105 gearing.

In testimony whereof we have hereunto set our hands.

THEODORE L. VALERIUS.
OLAF LARSEN.
